UNITED STATES PATENT OFFICE.

EDGAR H. COTTRELL, OF NEW YORK, N. Y., ASSIGNOR TO C. B. COTTRELL & SONS COMPANY, OF NEW YORK, N. Y., A CORPORATION OF NEW JERSEY.

PRINTING MACHINE.

1,072,702.

Specification of Letters Patent.

Patented Sept. 9, 1913.

Application filed May 22, 1911. Serial No. 628,772.

To all whom it may concern:

Be it known that I, EDGAR H. COTTRELL, a citizen of the United States, and resident of the borough of Manhattan, in the city 5 and State of New York, have invented a new and useful Improvement in Printing-Machines, of which the following is a specification.

This invention relates to printing machines and is directed particularly to shifting tympan holding devices.

The object of this invention broadly is to provide means for subjecting the shifting tympan to variations in pressure where- 15 by it will be subjected to one pressure while in its fixed position and to another pressure during its shifting operation.

The object of this invention more specifically is to provide a device which will hold 20 the tympan tightly against its cylinder by suction, said device being also arranged to blow the tympan away from the cylinder during the shifting operation, whereby the tympan is prevented from slipping when 25 in its fixed position and its shifting operation is materially facilitated.

A practical embodiment of this invention is represented in the accompanying drawings, in which—

30 Figure 1 shows the tympan holding device in side elevation, so much of a printing machine being shown as will give a clear understanding of the operation of the device, Fig. 2 is a partial end view and sec- 35 tion of the same, the shifting tympans and their operating mechanism being removed, Fig. 3 is a detail plan view of the perforated suction segment, Fig. 4 is a transverse section through the same, Fig. 5 is a detail 40 side view of the suction segment, and Fig. 6 is a detail cross section through the im- pression cylinder in the plane of one set of suction segments, the shifting tympans being shown in position thereon.

45 The impression cylinder is denoted by 1, which cylinder is herein shown as provided with a plurality of shifting tympans 2; the means shown in Fig. 6 for shifting the tympans at desired intervals may be oper- 50 ated by any well known or approved mech- anism, such, for instance, as that shown in the United States patent to Howard M. Barber, No. 996,902, granted July 24, 1911.

Hollow perforated tubes 3, in the form 55 of segments, are located circumferentially

in the periphery of the cylinder 1 at the desired points in the length of the cylinder, as, for instance, at points where they will engage the margins of the shifting tympans 2. The perforations 4 in these hollow segments 3 are located along their flattened exterior walls so that when the interior of these hollow segments are subjected to suction the perforations 4 will draw the tympan tightly against the cylinder and when the interior 65 of these hollow segments are subjected to air pressure the perforations 4 will blow the tympans away from their engagement with the cylinder.

The shaft 5 of the cylinder 1 is tubular in 70 form, its bore being denoted by 6. Pipes or passages 7 bring the interiors of the hollow segments 3 into open communication with the bore 6 of the hollow shaft 5. This shaft 5 is mounted in suitable bearings in 75 the side frames 8 of the machine.

A cylinder gear 9 is fast on the shaft 5 and is driven from a suitable driving gear 10 through an intermediate gear 11. The bore 6 of the hollow cylinder shaft 5 is pro- 80 vided with one or more holes 12 through its walls communicating with an annular cham- ber 13 in a collar 14 at one end of a pipe 15, which pipe 15 connects with an exhaust pump such, for instance, as a blowing en- 85 gine 16 through a branch pipe 17 and with a compressed air reservoir or tank 18 through a branch pipe 19.

A two-way cock 20 serves to open the pipe 15 either to the pipe 19 or the pipe 17 90 according to the position of the cock. A pipe 21 leads from the blowing engine 16 to the compressed air reservoir 18. The pipe 17 may be provided with a suction valve 22 so that air may be drawn into the 95 blowing engine even when the cock 20 closes communication between the pipe 15 and pipe 17.

The cock 20 is provided with an arm 23 which is connected to a two-armed lever 24 100 and 25 by a rod 26. An expansion spring 27 is arranged to exert its pressure in a di- rection tending to swing the arm 23 to open communication between the pipe 15 and the pipe 17. The movement of the arm 23 is 105 controlled by a cam 28 on a cam shaft 29 driven from a gear 30 on the shaft of the driving gear 10 through a gear 31. A rod 32 having one end attached to the arm 23 and its other end supported on the shaft 110

29 is provided with a cam stud or roller 33 engaging the face of the cam 28. A two-armed trip lever 34, 35, is pivoted at 36 and an expansion spring 37 engages the arm 35 tending to swing the same inwardly toward the shaft 5 of the cylinder. The arm 34 is provided with a notched portion 38 arranged to receive the free end of the arm 25 of the rock lever 24, 25. A pair of differential gears 39, 40, are provided with a lug 41 and a tappet 42 respectively, which are arranged to coact at certain intervals, in the present instance at the intervals when the tympans are to be shifted. The spring 37 serves to hold the arm 35 of the lever 34, 35, in position to be engaged by the head of the tappet 42 when the lug 41 coacts with the tappet for swinging the arm 35 outwardly a sufficient distance to lift the arm 34 out of its locking engagement with the arm 25 of the rock lever 24, 25.

The operation is as follows:—When the printing machine is in operation, except when the tympans are to be shifted, the cock 20 is in a position to open the pipe 15 to the pipe 17 thus causing the blowing engine 16 to exhaust the air from the hollow segments 3 through the pipes or passages 7, hollow shaft 5 and pipes 15 and 17. This will cause the tympan to be sucked snugly against the cylinder and thereby absolutely prevent the tympan from slipping. Just before the time for the tympans to be shifted, the lug 41 comes into contact with the tappet 42, causing the tappet to push the arm 35 of the rock lever 34, 35, outwardly thereby disengaging its arm 34 from the arm 25 of the rock lever 24, 25. At about this time, the surface of the cam 28 will recede thus permitting the spring 27 to swing the cock 20 into position to open communication between the pipes 15 and 19 and close communication between the pipes 15 and 17. This will permit the compressed air from the tank or reservoir 18 to escape through the pipes 19, 15, into the hollow shaft 5 and from thence outwardly through the perforations 4 in the hollow segments 3, serving to lift the shifting tympans away from the cylinder just before and during their shifting operation, thereby serving to materially assist in the shifting of the tympans. After the tympans have been shifted, the cam 28 will force the arm 23 of the cock 20 backwardly a sufficient distance to close communication between the pipes 15 and 19 and again open communication between the pipes 15 and 17 for subjecting the shifted tympan to suction. This movement of the arm 23 will also swing the lever 24, 25, back into position to be interlocked with the lever 34, 35, thereby holding the cock

20 in said position, until the differential gears 39, 40, again bring the lug 41 into coaction with the tappet 42.

65

It is to be understood that the perforations corresponding to the perforations in the hollow segments, are formed through any packing on the cylinder under the tympans so as to insure the subjection of the tympans to the suction and blowing action hereinabove described.

While I have shown this invention in connection with a cylinder having a plurality of tympans it is to be understood that the use of the same is not limited to any particular number of tympans.

It is also evident that various changes might be resorted to in the construction, form and arrangement of the several parts without departing from the spirit and scope of my invention; hence I do not wish to limit myself strictly to the structure herein set forth, but

85
What I claim is:—

1. In combination, a cylinder, a shifting tympan thereon and a common means for subjecting the tympan to one pressure while fixed and to another pressure when shifting.

90
2. In combination, a cylinder, a plurality of shifting tympans thereon and a common means for subjecting the tympans to one pressure while fixed and to another pressure when shifting.

95
3. In combination, a cylinder, a shifting tympan thereon and a common means for subjecting the tympan to suction while fixed and for removing the suction when shifting.

100
4. In combination, a cylinder, a plurality of shifting tympans thereon and a common means for subjecting the tympans to suction while fixed and for removing the suction when shifting.

105
5. In combination, a cylinder, a shifting tympan thereon, and a common means for holding the tympan against the cylinder by suction and for blowing the tympan away from the cylinder during the shifting operation.

110
6. In combination, a cylinder, a plurality of shifting tympans thereon and a common means for holding the tympans against the cylinder by suction and for blowing the tympans away from the cylinder during the shifting operation.

115
In testimony, that I claim the foregoing as my invention, I have signed my name in presence of two witnesses, this eighteenth day of May, 1911.

EDGAR H. COTTRELL.
